CLAIM

The ornamental design for a case for electronic communications device, as shown and described.

DESCRIPTION

FIG. 1 is a front perspective view of the case for electronic communications device showing my new design;
FIG. 2 is a rear perspective view thereof;
FIG. 3 is a front elevational view thereof;
FIG. 4 is a rear elevational view thereof;
FIG. 5 is a left side elevational view thereof;

FIG. 6 is a right side elevational view thereof;

FIG. 7 is a top plan view thereof;

FIG. 8 is a bottom plan view thereof;

FIG. 9 is a rear perspective view thereof showing the rear compartment cover component of the case in an open position;

FIG. 10 is a front perspective view of the inner shell component of the case shown separately for clarity of disclosure;

FIG. 11 is a rear perspective view of the inner shell component of the case shown separately for clarity of disclosure;

FIG. 12 is a front perspective view of the outer frame component of the case shown separately for clarity of disclosure;

FIG. 13 is a rear perspective view of the outer frame component of the case shown separately for clarity of disclosure;

FIG. 14 is a front perspective view showing the rear compartment cover component of the case in isolation for clarity of disclosure;

FIG. 15 is a rear perspective view showing the rear compartment cover component of the case in isolation for clarity of disclosure;

FIG. 16 is an exploded front perspective view showing the components of the case separated for clarity of disclosure; and,

FIG. 17 is an exploded rear perspective view showing the components of the case separated for clarity of disclosure. For clarity of disclosure, the components of the case for electronic communications device are shown in isolation in FIGS. 10-15 and separated in FIGS. 16-17. Although the case for electronic communications device, in which the claimed design is embodied, has an inner shell component, outer frame component, and rear compartment cover component, the claim is directed to the overall ornamental appearance of the case in its entirety and does not extend to the ornamental appearance of each of the individual components.
